MOP HOLDER

Edmund Preisser, New Britain, Conn.

Application April 26, 1937, Serial No. 138,886

2 Claims. (Cl. 306—3)

This invention relates to mops, dusters, and the like, and more particularly to a mop holder for adjustably holding a mop upon the end of a handle.

5 The aim of my invention is to provide a compact, sturdy mop holder of simple construction, inexpensive to manufacture, and easy to assemble, and which adjustably supports a mop at the end of a handle for universal movement.

10 It is a further object of my invention to provide a mop holder of the character described wherein a single clamping means serves the dual purpose of rigidly securing the holder to the end of a mop handle and secures a mop in desired 15 adjusted position.

It is a further object of my invention to provide an easily constructed mop holder of the character described wherein a single clamping bolt rigidly secures a pair of clamping members 20 to the end of a mop holder and frictionally engages a pair of jaws on a portion of a wire frame of a mop in such manner that the frame may be rotated between the jaws to reverse the mop.

It is a further object of my invention to provide 25 a mop holder rigidly secured to the end of a mop handle and arranged to pivotally receive and clamp over the open end of a wire frame forming part of a mop in such manner that the mop is supported for universal movement at 30 the end of a handle.

Other objects will be in part obvious and in part pointed out more in detail hereinafter.

The invention accordingly consists in the features of construction, combination of elements 35 and arrangement of parts which will be exemplified in the construction hereafter set forth and the scope of the application of which will be indicated in the appended claims.

In the accompanying drawings wherein I have 40 shown for illustrative purposes one embodiment of the present invention and wherein like numerals indicate like parts:

Figure 1 illustrates a front elevation of my mop holder assembled on the end of a handle and 45 supporting a mop having a closed wire frame;

Fig. 2 is a vertical section taken substantially along the line 2—2 of Fig. 1;

Fig. 3 is a side elevation of a clamping unit;

Fig. 4 is a sectional view taken along line 4—4 50 of Fig. 3;

Fig. 5 is a sectional view taken along the line 5—5 of Fig. 3;

Fig. 6 is a perspective view of the parts shown 55 in Fig. 3;

Fig. 7 shows a mop formed upon an open end wire frame; and

Fig. 8 shows a mop formed upon a closed wire frame.

In accordance with my invention, I have provided a mop holder composed of two similar opposed spaced clamping units A arranged to be removably secured in cooperative embracing relation on the bottom of a suitable handle, such as a mop handle 10, by a bolt 11 and wing nut 12. 5 These units also include two opposed pivotal jaws 13 which are urged towards each other by the bolt and nut into frictional clamping relation about a wire frame 14 rotatably received between the jaws and forming part of a mop M. The 10 rotation of the frame within the jaws and the pivotal movement of the jaws provides a universal support for the mop on the handle.

In the present instance, the mop is illustrated 20 as of conventional form having a multiplicity of cords or mop members M' bound together between a twisted pair of wires forming the mop frame. The frame may comprise a closed loop having a central cross bar 14', as shown in Fig. 8, and adapted to be rotatably received and clamped 25 between the jaws 13, or the frame may be composed of an open end loop having a pair of spaced depending ends 14'', as shown in Fig. 7, and adapted to be received in the clamping jaws in a manner to be later described.

Each of the units A has an elongated partially cylindrical sheet metal clamping member 15 shaped to fit in embracing engagement with, and to generally conform with, the rounded cylindrical end of mop handle 10. Bolt 11 passes 30 through transversely extending aligned holes in members 15 and in handle 10, as shown in Fig. 2, and wing nut 12 serves to clamp the members 35 tightly against the handle. As shown in Fig. 2, one of these holes is threaded as at 15' to receive 40 bolt 11 and non-rotatably support it adjacent its head, and the other hole 15'' freely receives the bolt so that turning of the wing nut may conveniently control the clamping operation.

Each member 15, as shown in Fig. 2, extends 45 a corresponding distance beyond the end of handle 10 and is bent inwardly, terminating in a substantially flat flange 16 lying in a plane longitudinally of the handle, thus providing a pair of opposed substantially parallel flanges spaced 50 closer than the diameter of handle 10. A pair of opposed spaced jaws 13, suitably formed as of sheet metal bent to shape and having spaced 55 angularly divergent side walls 17 and 18 interconnected by bottom walls 19, are respectively and

pivots secured to members 15 by rivets 20 passing through bottom walls 19 and flanges 16. These rivets are axially aligned and disposed transversely of the handle so that the frame of the mop which is clamped between the jaws may assume a pivotal movement transversely of the handle as well as rotate within said jaws, thus providing a substantially universal movement of the mop with relation to the handle. If the mop 10 is of the construction shown in Fig. 8, frame portion 14' is free to turn through more than 180° in the jaws 13 so that the mop may be easily reversed in the holder. Jaws 13 are preferably so positioned relative to each other that tightening 15 of wing nut 12 will first frictionally engage the jaws in clamped relation about wire frame 14 and frictionally engage bottom walls 19 with flanges 16, after which further clamping movement of the wing nut will tighten clamping members 15 20 into tight embracing relation with the bottom of the handle. Hence, the clamping bolt and wing nut serve the dual feature of clamping both the mop in adjusted position and the holder to the handle.

25 In order to conveniently support a mop having an open end wire frame as illustrated in Fig. 7, the walls 18 of each jaw are cut away between their ends providing a pair of corresponding apertures 21 through which the ends 14" of the 30 mop frame may freely extend. It will be noted that bottom wall 19 does not extend beyond its junction with side walls 18 within the aperture 21, and the extended ends 14" of the wire frame will be received within the space between the 35 clamping members 15 and beyond the end of the handle 10. In view of the fact that these members are parti-cylindrical and are bent inwardly at their ends to provide flanges 16, pockets 22 will be provided to receive the extended ends 14" 40 of the wire frame and permit ample angular movement of the wire frame within the holder.

As many changes could be made in the above construction and many apparently widely different embodiments of this invention could be 45 made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of 5 language, might be said to fall therebetween.

I claim as my invention:

1. In a mop holder for adjustably securing the wire frame of a mop at the end of a mop handle, a pair of similar opposed parti-cylindrical clamp- 10 ing members receiving the end of the mop handle and extending therebeyond, said extended portions terminating in a pair of parallel spaced flanges overlying a portion of the mop frame, op- 15 posed clamping jaws frictionally and rotatably receiving said portion of the frame and located between said flanges, said jaws having divergent spaced side walls interconnected by opposed bot- 20 tom walls, aligned rivets respectively pivotally connecting the bottom walls and flanges, the 25 axes of jaw movement and frame movement intersecting substantially at right angles, and a bolt removably securing the clamping members to the frame and maintaining the mop frame in any adjusted position.

2. In a universally adjustable mop holder, a 30 mop frame comprising an open end loop, the ends of said loop being right-angled to provide lateral projections, a pair of clamping members arranged to receive the lower end of a mop handle and having their forward ends extending therebeyond and straddling the spaced open right-angled ends of said mop frame, opposed channel shaped 35 clamping jaws between said forward ends of said clamping members frictionally and rotatably re- 40 ceiving the frame adjacent the lateral projections, said jaws having notches in corresponding side edges through which said frame ends freely extend towards the handle, aligned rivets respectively and pivotally connecting the jaws to the forward ends of said clamping members, the 45 axes of jaw movement and frame movement intersecting substantially at right angles, and a bolt removably securing said clamping members, jaws, and frame in adjusted position.

EDMUND PREISSER.
